(57) CLAIM

The ornamental design for a waterproof cover for sports bags, as shown and described.

DESCRIPTION

FIG. 1 is a front elevation view of a waterproof cover for sports bags showing my new design;

FIG. 2 is a rear elevation view thereof;

FIG. 3 is a right side elevation view thereof, the opposite side being a mirror image of the shown;

FIG. 4 is a top plan view thereof;

FIG. 5 is bottom plan view thereof; and,

FIG. 6 is an in-use isometric view thereof.

The broken lines in FIG. 6 of the drawings depict environmental subject matter only and form no part of the claimed design.
